US00D883248S

(12) **United States Design Patent** (10) **Patent No.:** **US D883,248 S**
Zhang et al. (45) **Date of Patent:** **** May 5, 2020**

(54) **NETWORK CONFERENCE TELEPHONE APPARATUS**

(71) Applicant: **YEALINK (XIAMEN) NETWORK TECHNOLOGY CO., LTD.**, Xiamen, Fujian (CN)

(72) Inventors: **Jian Cheng Zhang**, Fujian (CN); **Wei Cen Xu**, Fujian (CN); **Chun Sheng Su**, Fujian (CN); **Jing Feng Su**, Fujian (CN); **Lian Chang Zhang**, Fujian (CN); **Ji Wei Zhou**, Fujian (CN)

(73) Assignee: **YEALINK (XIAMEN) NETWORK TECHNOLOGY CO., LTD.**, Xiamen (CN)

(**) Term: **15 Years**

(21) Appl. No.: **29/686,837**

(22) Filed: **Apr. 8, 2019**

Related U.S. Application Data

(62) Division of application No. 29/617,476, filed on Sep. 14, 2017.

(30) **Foreign Application Priority Data**

Primary Examiner — Marie D. Fast Horse

(57) **CLAIM**

The ornamental design for a network conference telephone apparatus, as shown and described.

DESCRIPTION

FIG. 1 is a perspective view of a network conference telephone apparatus showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

All broken lines in the drawings depict portions of the network conference telephone apparatus that form no part of the claimed design.

1 Claim, 7 Drawing Sheets
